PAPER ROLL HOLDER

Lester Morton White, Vancouver, British
Columbia, Canada

Application November 8, 1934, Serial No. 752,151

1 Claim. (Cl. 242—55.2)

My invention relates to improvements in paper roll holders and paper rolls therefor, which are particularly adapted for use on holders in which the matrix and paper roll are neither oscillating or rotative.

The object of the invention is to provide means for securing the roll on the matrix in such a manner that it cannot be removed except by tearing it off strip by strip.

10 The invention consists of a wall member having a matrix supported therefrom and a plunger extending from the wall member to engage the matrix intermediate its length and to secure a roll of paper fitted upon said matrix against removal, as will be more fully described in the following specification and shown in the accompanying drawing, in which:—

Fig. 1 is a vertical sectional view of the paper roll holder.

20 Fig. 2 is a perspective view of the paper roll. In the drawing like characters of reference indicate corresponding parts in each figure.

The numeral 1 indicates a wall member having a front panel 2 provided with a horizontal slot 3 through which a jet of air is adapted to be forced by a manually operated flap 3A when it is desired to take a strip of paper from the roll 4.

Extending from one side of the wall member 1 is a support 5 carrying a matrix 6 for the paper roll. The matrix is a hollow body having front and rear walls respectively numbered 7 and 8, the front wall 7 is provided with a finger opening 9 which is obviously covered by the paper roll when the device is in use. Fitted to the front wall is a spring latch 10 having an upturned free end 11 which is adapted to reach into approximate contact with the rear wall 8 of the matrix 6.

40 A tubular socket 12 is secured to the wall member 1 and extends inwardly from the front panel 2. Slidably fitted into the socket 12 is a plunger 13 which is urged outwardly by a spring 14. The plunger 13 is provided with a conical point 15 at its free end and is grooved immediately to the rear of said point as at 16, it is also provided to

the rear of the groove with a shoulder 17 which is adapted to abut the outside of the rear wall 8, while the point 15 and groove 16 are adapted to enter the matrix 6 through an aperture 18, so that the upturned end 11 of the latch 10 may engage the groove 16 to prevent the plunger from being withdrawn from its extended or normal position.

The paper roll 4 is fitted in the usual manner on a cardboard tube 19 and is perforated or otherwise weakened transversely of the paper strip as at 20. An aperture 21 is formed through the roll and its tube 19 along the line of weakness 20 which is capable of admitting the plunger.

In use, the plunger 13 is thrust back into its socket 12 to permit a roll 4 to be placed on the matrix 6, when the plunger is released it is forced by the spring 14 through the aperture 21 in the roll and into the aperture 18 in the matrix, when fully extended it becomes engaged by the free end 11 of the latch 10 which enters the groove 16 to prevent said plunger from being retracted and the roll being removed from the matrix. When the roll has been used up by successively tearing off strips of paper therefrom, its cardboard tube 19 is torn off and by inserting the finger through the aperture 9 the latch 10 can be depressed so that the plunger 13 may again be thrust back into its socket to fit another roll to the matrix.

30 What I claim as my invention is:

In a paper roll holder adapted to dispense strips from a paper roll carried thereby, a wall member, a matrix supported therefrom, a plunger extensible from the wall member to the matrix, said matrix having an aperture in alignment with the plunger, said plunger being adapted when extended to enter the aperture of the matrix and a latch within the matrix adapted to lock the plunger in extended position, said matrix having an opening normally covered by the paper roll affording access to the latch.

LESTER MORTON WHITE.
